(57) **CLAIM**

The ornamental design for a bath chair, as shown and described.

DESCRIPTION

FIG. 1 is a top, front perspective view of a bath chair in a reclined sitting position showing my new design.

FIG. 2 is a right side elevational view thereof.

FIG. 3 is a left side elevational view thereof.

FIG. 4 is a top plan view thereof.

FIG. 5 is a front elevational view thereof; and,

FIG. 6 is a rear elevational view thereof.

The broken line showing of portions of the chair frame is for illustrational purposes only and forms no part of the claimed design.
